UNITED STATES PATENT OFFICE.

JOHN L. BALTZER AND LAROY S. STARRETT, OF ATHOL, MASSACHUSETTS, ASSIGNORS TO THE L. S. STARRETT CO., OF ATHOL, MASSACHUSETTS, A CORPORATION OF MASSACHUSETTS.

BASE ATTACHMENT FOR CENTER-GAGES.

No. 813,997.

Specification of Letters Patent.

Patented Feb. 27, 1906.

Application filed December 5, 1904. Serial No. 1235,493.

To all whom it may concern:

Be it known that we, JOHN L. BALTZER and LAROY S. STARRETT, of Athol, in the county of Worcester and State of Massachusetts, have invented certain new and useful Improvements in Base Attachments for Center-Gages, of which the following is a specification.

This invention is designed to provide a convenient base or seat for a center-gage or the blade of a steel square, the device serving to instantly locate the gage or blade edge-wise and lengthwise in the radial axial plane of any shaft or like body to which the seat may be applied. The gage will also be perpendicular and its edges parallel to any plane surface to which said base or seat is applied.

In the drawings, Figure 1 is a side elevation showing a center-gage in position in this supporting-base. Fig. 2 is a vertical section on line 2 2 of Fig. 1. Fig. 3 is an enlarged horizontal section of the base and its spring, taken about on line 3 3 of Fig. 4. Fig. 4 is an end view of the device, the blade or gage removed.

As represented, our improved base or seat is a milled cylindrical metal block 6, from which a rectangular longitudinal segment has been removed, leaving in its bottom a recess 7, extending from end to end and bounded by diverging radial planes. The edges where these planes meet the periphery are slightly flattened horizontally, so that the base-block will rest smoothly on a plane surface. The shape of the base-block and the inclination of the recess-walls may be modified. Directly above the center of recess 7 the base or seat 6 has a longitudinal groove or slot 8 with vertical edge walls and a horizontal bottom parallel to the plane of the flattened lower edges of the block, so that the gage or blade 5 when secured therein will stand vertically on a horizontal surface with its edges parallel to the axis of the base. The slot 8 is wider than the thickness of the gage;

so as to receive a longitudinal spring 9, serving to hold the gage frictionally against one wall of the slot.

The spring shown is of peculiar construction. It extends on a uniform curve from end to end of the base, a portion 10 of each end being bent outwardly to overlap the end of the base-block, which is slightly recessed to receive it. (See Fig. 3.) This permits repeated insertion and removal of the gage or blade without displacing the spring. The body of the spring rises above the base-block, preferably on a curve, as in Fig. 1, so that the gage may be inserted into the slot by first pressing it against the convex side of this protruding portion and introducing it edge-wise. Obviously it may be inserted endwise.

We claim as our invention—

1. A base or seat for a center-gage, the same comprising a rigid elongated body having in its bottom a continuous longitudinal recess with diverging walls and flattened lower edges, and formed in its top with a vertical longitudinal groove or slot immediately above the axis of said body, in combination with a spring mounted in such groove or slot, rising above the walls thereof on a uniform curve, and adapted to hold the gage or blade frictionally against the vertical wall of said groove, substantially as set forth. 75

2. The elongated base-block 6 having a rectangular recess 7 with radial walls flattened terminally and above it a vertical longitudinal slot 8, with spring 9 therein, anchored terminally to the base-block and adapted to hold the tool frictionally against the slot-wall, substantially as set forth. 80

In testimony whereof we have affixed our signatures in presence of two witnesses.

JOHN L. BALTZER.
LAROY S. STARRETT.
